UNITED STATES PATENT OFFICE.

WILLIAM E. CODY, OF CHICAGO, ILLINOIS.

DISPLAY DEVICE.

Application filed November 24, 1919. Serial No. 340,380.

To all whom it may concern:

Be it known that I, WILLIAM E. CODY, a citizen of the United States, residing at Chicago, in the county of Cook and State of Illinois, have invented certain new and useful Improvements in Display Devices, of which the following is a specification.

My invention relates to a display device for merchandise, and particularly to a knock-down display device for exhibiting merchandise such as candies, nuts and the like which often are furnished in boxes with the contents arranged in trays or layers, so that the contents of the box may be supplied to the trade without removing the device from the boxes and so that a portion may be used for display.

It is an object of my invention to provide a knock-down display device for boxed merchandise which device may be readily applied to boxes wherein candies, nuts and similar goods are exhibited by the dealer for display purposes, so that the goods may be properly displayed and arranged in the boxes in such manner as to be readily removed for sale, at the same time presenting a portion of the contents for inspection of the purchaser.

I accomplish the objects of my invention by providing a knock-down display device consisting of side members having projections for engaging the top edges of the sides of the box, an end member for connecting the ends of the sides, a glass or other transparent cover member suitably supported by said members, and a hinged cover or rear member, all of which parts may be readily assembled and disassembled by means of co-operating elements on the various parts, which are so arranged that they may be readily shipped in a knock-down condition and easily assembled for display purposes.

The preferred form of my invention I have shown in the accompanying drawings, in which—

Figure 1 is a vertical sectional view through a knock-down display device as mounted on the top of a box in which the goods are contained in a top tray and in bulk below the tray;

Figure 2 is a top plan view of the arrangement of Figure 1; and

Figure 3 is an end elevation of the arrangement of Figure 1, looking at the left-hand end thereof.

The device or box in combination in which I have chosen to illustrate my invention is represented at 5, and contains a tray A, in which a portion of the merchandise, such as candies, nuts or the like are placed for shipment, the merchandise also filling the space below the tray. The knock-down display device comprises two side members 6 formed of a light yet relatively strong material such as tin and which have lugs 7 formed integrally therewith for overlying and engaging the tops of the side edges of the box 5. I prefer to assemble the display device so that the lower edges of the side members 6 will extend inwardly of the side edges of the box for more securely maintaining the device in position. Preferably the side members are triangular in elevation so as to form a sloping cover for the box.

For connecting the front ends of the sides 6 an end member 8 having rearwardly extending tongues 9 is provided, these tongues engaging integrally formed stirrups or loops 10 in the sides 6. The top edges of the sides 6 and the end member 8 are bent at right angles to form top ledges 11 and 12 for overlying the edges of the glass or other transparent top member 13. Just below the inturned edges 11 and 12 of the side and end members 6 and 8 are formed integrally extending brackets 14 for supporting the transparent top 13. As a means for holding the tray A of the box immediately beneath the transparent top 13, I provide cross braces 15 having downwardly turned ends 16 for hooking engagement with loops or stirrups 17 formed in the side members 6, similar to the engagement between the inturned ends 9 of the end member 8 and the stirrups or loops 10. I have shown two such cross braces 15, but it is understood that as many may be provided as are necessary to support the particular merchandise to be displayed. As a rear end member for the display device, I prefer to provide a cross bar 18 adapted to engage suitably arranged apertures in ears 19 of the sides 6, and on the bar 18 is hinged a U-shaped member 20 adapted to receive the rear end of the cover member 13 and a hinged member or door 21, the latter being sufficiently long to rest against the rear ends of the sides 6 when the parts are assembled and sufficiently wide to extend downwardly to at least the top edge of the box 5, whereby the door member 21 may be 110

lifted, permitting access to the interior of the box for removal of the contents.

The operation of my invention is as follows:

5 The two side members are joined at the front ends by bringing the front end member 8 into engagement therewith, so that the tongue 9 of the member 8 will engage the stirrups 10. The cross braces 15 are then 10 hooked in the loops 17. The glass top member 13 is then slid in place between the in-turned edges 11 and 12 of the sides and end members and supported on the lugs 14, as is clearly shown in the drawings. The rear 15 end member is then applied by causing the bar 18 to engage the apertured ears 19 of the sides 6 and the member 20 to engage the glass top 13, whereupon the tray A will be slid onto the cross braces 15 for support immediately beneath the transparent cover 13, as is clearly shown in the drawings. The 20 merchandise in the tray A will therefore be undisturbed and will be fully protected while being displayed. By reason of the 25 hinged cover 21 the interior of the box is suitably closed against the admission of dust and the like, while permitting access thereto. It will readily be observed that by my invention a portion of the contents of the 30 box may be presented for inspection by the purchaser and at the same time protected, as is also the balance of the contents of the box. The fact that the display device is made knock-down makes possible the use 35 of it successively on different boxes.

I have shown my invention as it appears when in use with merchandise that is packed in a top tray and in bulk below the tray. It is useful, however, for displaying any kind 40 of merchandise which may be kept in the original container, even though the merchandise is not packed in a tray. For instance, if the box contains goods entirely in bulk, a tray or shelf may be substituted 45 in place of the tray A and supported on braces 15, and a portion of the contents of the box placed thereon. Then if it were desired to remove a portion of the contents of the box, removal would be permitted by reason of the hinged door 21 permitting access 50 to the interior of the box.

An advantage of my invention lies in the fact that the goods displayed do not indicate the quantity still remaining in the container. There are some devices on the market which, while permitting inspection of the goods in the container, yet show the amount of goods which have been removed and the quantity still remaining. This may 55 or may not be an important feature, but the elimination of such a feature adds to the attractiveness of the display device for displaying such merchandise as candies, nuts and the like. It is understood that any 60 merchandise shipped in the original con-

tainer may be sold from the same container by use of the device embodying my invention. As before stated, the adaptability of my device is such that it may be readily made to conform to any shape or size of 70 container that is generally used by the dealer to present the goods to customers, and irrespective of the material of which the container is made.

It will be noted that all of the cooperating 75 elements whereby the various members of my device are secured together in knock-down relation are preferably integrally formed, so that the cost of manufacture of my device is reduced to the minimum and there is but slight waste in forming any of the various cooperating elements.

80 My invention would eliminate the necessity for wrapping individual pieces of candy and the like, as is done at the present time. Some kinds of confections are now sold wrapped in foil or other wrappers solely for the purpose of keeping them clean while being displayed and moved about from container to display shelves or trays and while 85 being delivered to the purchaser.

90 While I have described more or less precisely the details of construction of my invention, I do not wish to be understood as limiting myself thereto, as I contemplate 95 changes in form and the proportion of parts and substitution of equivalents as circumstances may suggest or render expedient, without departing from the spirit of my invention.

100 I claim:

1. A display device adapted to be associated with the open top of a merchandise box, said device comprising means for displaying a portion of the contents of the box, and means for permitting access to said box below said displayed portion, said means jointly comprising a cover for the open top of the box.

105 2. A knock-down display device for boxed goods, including in combination a pair of side members, an end member for joining the front ends of said side members, a hinged member adapted to serve as a rear member of the device, said members being provided with cooperating elements for removably retaining said portions in assembled relation, a transparent cover, means carried by said members for maintaining said cover in position, and means cooperating with certain of 110 said members for supporting a portion of the contents of the box clear of the box and adjacent said cover.

115 3. A knock-down display device for boxed merchandise including side members having integrally formed projections for engaging the top edges of the box, an end member adapted for connection with the ends of said side members, braces cooperating with said side members serving with the end members 120

130

as means for forming a unitary structure, a transparent top member associated therewith, means for supporting a portion of the contents of the box immediately below the top and clear of the balance of the contents of the box, and a rear member having hinged connection with the side members adapted for permitting access to the box while said device is in position thereon.

10 4. A knock-down display device for boxed merchandise including side members substantially triangular in elevation, end members cooperating with said sides to form a unitary structure, one end member having a hinged portion adapted to serve as a door, braces removably engaging said side members, cooperating elements whereby said braces and end members may be joined with the sides to form a unitary structure, said 20 side members having portions thereof formed integrally therewith whereby the device may be supported as a whole on a box and whereby the top member may be supported therein, and means for presenting for 25 display a portion of the contents of the box immediately beneath said top.

5. A knock-down device for displaying boxed goods including a pair of side members adapted to extend within the top of the 30 box and having integrally formed projections for engaging the box sides to position the same thereon, an end member adapted to removably engage the front ends of said sides, said side and end members having interfitting parts, cross-braces adapted to removably engage said side members and cooperate with the front and side members to 35 form a unitary structure, a glass top for said structure, said members having means for supporting the top in said structure, a rear member adapted to removably engage the side members and having a hinged portion adapted to serve as a door whereby access to the interior of the box may be had while said 40 structure is supported thereon, and means for supporting a portion of the contents of

the box immediately beneath said glass for display purposes.

6. A display device adapted to be associated with the open top of a merchandise box, 50 said device comprising an inclined fixed portion part of whose area is transparent and the lower edge of said portion approximately engaging an edge of the box, and a hinged portion connecting the upper edge of the 55 member and the opposite edge of the box.

7. A display device adapted to be associated with the open top of a merchandise box, said device comprising an inclined fixed portion part of whose area is transparent 60 and the lower edge of said portion approximately engaging an edge of the box, and a hinged portion connecting the upper edge of the 65 member and the opposite edge of the box, both said portions being supported from said box by fixed, laterally placed, vertically extending members.

8. A display device adapted to be associated with the open top of a merchandise box, 70 said device comprising an inclined fixed portion part of whose area is transparent and the lower edge of said portion approximately engaging an edge of the box, and a reversely inclined portion hingedly connected to the upper edge of said first portion and having 75 its lower edge engaging the opposite edge of the box.

9. A display device adapted to be associated with the open top of a merchandise box, 80 said device comprising an inclined fixed portion part of whose area is transparent and the lower edge of said portion approximately engaging an edge of the box, and a reversely inclined portion hingedly connected to the upper edge of said first portion and having 85 its lower edge engaging the opposite edge of the box, both said portions being supported from said box by fixed, laterally placed, vertically extending members.

Signed at Chicago, Illinois, this 12th day 90 of November, 1919.

WILLIAM E. CODY.
